UNITED STATES PATENT OFFICE

OTTO WEEBER AND OTTO SOLDAN, OF BERLIN, GERMANY, ASSIGNORS TO SIEMENS & HALSKE AKTIENGESELLSCHAFT, OF SIEMENSSTADT, NEAR BERLIN, GERMANY

DESIGN FOR A DESK TELEPHONE

Application filed October 12, 1931, Serial No. 41,378, and in Germany April 29, 1931. Term of patent 14 years.

To all whom it may concern:

Be it known that we, OTTO WEEBER and OTTO SOLDAN, both citizens of the Republic of Germany, residing at Berlin, Germany, have invented a new, original, and ornamental Design of a Desk Telephone, of which the following is a specification, reference being had to the accompanying drawings, forming a part thereof.

Figures 1 and 2 are perspective views of the desk telephone, showing our new design.

We claim:

The ornamental design for a desk telephone as shown.

In testimony whereof we have hereunto set our hands this 21st day of September, 1931.

OTTO WEEBER.
OTTO SOLDAN.
